UNITED STATES PATENT OFFICE.

SOLL FREEMAN, OF CHICAGO, ILLINOIS.

GARAGE.

Application filed April 5, 1926. Serial No. 99,700.

My invention relates to garages.

One of the objects of my invention is to provide a storage arrangement for garages which will make it easy to get the cars into 5 and out of their storage space quickly and without damage or injury to the car.

A further object of my invention is to provide a garage arrangement in which the cars can be readily moved from their storage space to a washing space provided, without the necessity of starting the car or moving it under its own power, thereby materially saving gasoline and wear and tear 10 on the car.

15 A further object of my invention is to provide a construction which will facilitate the making of minor repairs, enabling them to be made without running the car under its own power.

20 A further object of my invention is to provide an improved heating arrangement for garages.

Further objects will appear from the description and claims. In the following, in 25 which an embodiment of my invention is illustrated,

Figure 1 is a diagrammatic sectional plan view showing part of a garage arranged in accordance with my invention;

30 Fig. 2 is a vertical section substantially on the line 2—2 of Fig. 1, and

Fig. 3 is a detail view showing the ramp arrangement.

Referring to the drawings in detail as 35 shown in Fig. 1, the floor plan of the garage is divided into parallel driving lanes 1 with an entrance and exit at each end of each lane, and with storage space 2 on each side of each lane. In practice the driving lanes 40 will be about 9 ft. wide and the storage strip on each side of each lane will be about 6 ft. wide. A transversely movable float or carriage 3 is provided for each car, these floats having wheels 3^a traveling on tracks 4 extending 45 transversely of the driving lanes and into the storage space at the sides of the driving lanes. Each float is provided with a hinged ramp 5 at each end to facilitate driving onto and off from the float. The 50 surface of each float may be about 6" above the surface of the driving lane. Each carriage or float on one side of the driveway lies directly opposite a carriage on the opposite side of the driveway, and each pair of 55 these oppositely disposed carriages travels on the same set of tracks. I have shown

three tracks or rails for each pair of carriages or floats, one rail being located underneath the central portion of the carriages and the other two rails being located at the 60 respective ends of the carriages. This prevents any undue strain on the carriages.

As shown in Fig. 3, the foldable ramps are so arranged that when two adjacent carriages are pulled out into the driveway so 65 that they lie end to end, the ramp of one carriage will fold down on top of the ramp of the other carriage so as to lie in substantially horizontal position and form in effect a bridge between the two carriages, so that in 70 case of emergency, if it should be desired to get all of the cars out of the garage quickly, the cars could be driven directly from one carriage on to another and thus on down the driveway and out of the garage. 75

The fact that the ramps can be folded down on top of the platform when the platform is in the storage space results in a conservation of the storage space, as otherwise, if the ramps could not be folded up, additional storage space would be required for 80 these ramps.

In the normal use of the garage, anyone wishing to store his car drives down the lane to the space allotted to him where his carriage or float is pulled out on its tracks so 85 as to be in the middle of the driving lane. He then drives his car onto this float, throws on the brakes, folds up the ramp and then shoves the float to the storage space at the 90 side of the driveway. The ramp at the farther end of the carriage during this operation is folded up on top of the float and may act as a stop to prevent the driver from driving off the farther end of the float. Each 95 float is at least as long as the wheelbase of a car and is preferably about 15 ft. long, long enough to accommodate the largest cars.

The platform is substantially co-extensive 100 with the car stored thereon and provides a convenient support for a mechanic in making minor repairs on the car, enabling him to work with ease on any part of the car without coming in contact with the dirt and 105 grease on the garage floor.

In this arrangement it will be seen that the cars may be quickly and compactly stored, and there is no danger of one car bumping into another and thus injuring the 110 fenders, etc.

A water supply line is provided on each

side of each driving lane in the form of an extension hose 6, the loops of which are supported by pulley carriages 7 running on a track. With this arrangement the nozzle 8 can be brought to any desired part of the driving lane so that any car can be pulled out on its float into the middle of the driving lane and there washed without the necessity of moving the car under its own power with the resultant wear and tear on the car and consumption of gasoline.

10 A heating supply line 9 is also provided extending parallel and along side each lane and between two rows of cars so that rows 15 of cars can be kept warm by a single pipe line and freezing prevented.

20 While I have described but one embodiment of my invention, it is obvious that many modifications therein may occur to those skilled in the art, and I desire, therefore, that my invention be limited only by the scope of the appended claims and by the prior art.

I claim:

25 1. A garage construction comprising a driveway for the cars, a storage space at one side of the driveway and a plurality of carriages, one for each car to be stored, individual to the storage space for each car, 30 for carrying the car transversely from the driveway to its individual storage space at the side of the driveway, each carriage being provided with a ramp which folds up on top of the carriage when the carriage is 35 in the storage space, whereby storage space is conserved, said carriages being so close to each other endwise that the ramp of one carriage folds down on top of the ramp of an adjacent carriage to provide a bridge between the carriages when the carriages are 40 pulled out into the driveway.

2. A garage construction comprising a plurality of parallel driveways for the cars, storage space on both sides of said driveways for storing a row of cars on each side of each driveway, and a plurality of carriages, one for each car, for conveying a car transversely from the driveway to its individual storage space at one side or the 45 other of the driveway, each carriage on one side of the driveway being directly opposite the carriage on the other side of the driveway.

50 other of the driveway, each carriage on one side of the driveway being directly opposite

the carriage on the other side of the driveway.

3. A garage construction comprising a plurality of parallel driveways for the cars, storage space on both sides of said driveways for storing a row of cars on each side of each driveway, and a plurality of carriages, one for each car, for conveying a car transversely from the driveway to its individual storage space at one side or the other of the driveway, each carriage on one side of the driveway being directly opposite the carriage on the other side of the driveway, and water supply connections located in the space between the car storage space for one driveway, and the car storage space for an adjacent driveway for use in washing the cars in both said storage spaces.

4. A garage construction comprising a plurality of parallel driveways for the cars, storage space on both sides of said driveways for storing a row of cars on each side of each driveway, and a plurality of carriages, one for each car, for conveying a car transversely from the driveway to its individual storage space at one side or the other of the driveway, each carriage on one side of the driveway being directly opposite the carriage on the other side of the driveway, and heat supply connections located in the space between the car storage space for one driveway and the car storage space for an adjacent driveway for heating the cars in both said storage spaces.

5. A garage construction comprising a plurality of parallel driveways for the cars with entrance and exit openings at each end of each lane, storage space on both sides of said driveways for storing a row of cars on each side of each driveway, and a plurality of carriages, one for each car, for conveying a car transversely from the driveway to its individual storage space at one side or the other of the driveway, each carriage on one side of the driveway being directly opposite the carriage on the other side of the driveway.

In witness whereof, I have hereunto subscribed my name.

SOLL FREEMAN.
